SASH BALANCE

Leo Hirsh, Los Angeles, Calif.

Application February 7, 1939, Serial No. 255,129

1 Claim. (Cl. 16—198)

This invention relates to window hardware, and more especially to sash balances of the spring type for the supporting of window sash and holding them in partially opened and closed positions.

An object of the invention is to provide a simple, practical and inexpensive device of the character described.

Another object is to provide an improved spring type sash balance having simplified construction and improved operating characteristics.

A further object is to provide a sash balance adapted for the operation of two sash and one that may be easily installed and requiring a minimum of space.

Other objects and advantages will appear and be brought out more fully in the following specification, reference being had to the accompanying drawing, wherein

Fig. 1 is an elevation view of an embodiment of my invention with the cover plate removed.

Fig. 2 is a side view of the same mounted in a window jamb and showing a portion of one of the sash, and

Fig. 3 is a sectional view taken along the line 3—3 of Fig. 1.

Referring more particularly to the drawing, I show a sash balance comprising a mounting plate 5, preferably of cast iron or other suitable material, having a lower flange portion 6 and an upper curved flange portion 7. Plate 5 is provided with a pair of posts 8, preferably formed integrally therewith and adapted to support and secure a flanged cover plate 9 by use of screws 10. Plate 9 is secured by screws 11 to the window jamb 12 which is suitably recessed to admit the sash balance therein.

A pair of hollow studs 13 are secured to member 5 in any suitable manner or formed integrally therewith and provide bearings for a pair of hubs 14. Posts 13 each have a cut out portion 15 adapted to admit one end of a spring 16, the other end of which is secured to a flange 17 formed within hub 14. A steel ribbon 18 has one end carried several times around each hub 14 and suitably secured thereto, and flange 6 is provided with a pair of cut out portions 19 whereby the ribbons may be passed therethrough, the ribbons each being secured to a hook 20 and suitably secured to the lower portion of the sash 21.

The window jamb 12 is provided with a sloping cut out portion 22 adjacent cut out 19 to permit ribbons 18 to be twisted a quarter turn so as to lie flat between the edge of sash 21 and jamb 12 thereby requiring a minimum of space.

The operation of the invention should be obvious from the foregoing description, sash 21 being supported by ribbons 18 are held in position by tension thereon exerted from springs 16 although they may be raised and lowered and held in intermediate positions by the springs 16 which substantially counterbalance the weight of the sash.

By my novel arrangement of the quarter turn in the ribbons 18, the sash balance may be mounted flat in the jamb 12 thus requiring a minimum of space and permitting the use of steel ribbons 18, being a more satisfactory construction than the use of cables which are subject to breakage under constant use.

It will be further clear that my sash balance constructed as hereinabove described is of greater simplicity than heretofore known, comprising essentially two casing members, that is plate 5 and cover 9, the latter being readily removable if necessary for adjustment or lubrication of the moving parts without disturbing the position of plate 5 in the window jamb.

Having described my invention, what I claim is:

A sash balance as described, comprising a base plate having a lateral flange at each end, a cover plate resting on said flanges and extending beyond the same and forming securing means, said cover plate having inwardly turned flanges at its sides extending over the side edges of the base plate, posts carried by the base plate intermediate the ends thereof and extending out flush with the flanges, screws passing through the cover plate and screwed into said posts forming a closed housing, studs carried by the base plate above and below the posts, a hub rotatably mounted on each stud, a coil spring within each hub and having one end secured thereto and the other end secured to the stud, and ribbons secured to the hub and wound thereon and the free ends passing downwardly from opposite sides of the hubs through openings in the lower flange of the base plate.
